TOY FINGER PUPPET

David S. Matteson, Fort Lauderdale, Fla., assignor to
The Broward County School Board, Fort Lauderdale, Fla.

Filed Aug. 6, 1971, Ser. No. 122,650

Term of patent 14 years

Int. Cl. D21—01

U.S. Cl. D34—2 R

FIG. 1

Des. 226,438

PAGE 2

FIG. 2

FIG. 3

FIG. 1 is a front elevational view of a toy finger puppet showing my new design;

FIG. 2 is a perspective view thereof; and

FIG. 3 is a side elevational view thereof.

I claim:

The ornamental design for a toy finger puppet, as shown.
